UNITED STATES PATENT OFFICE.

UNO E. TUOMI, OF DALLAS, TEXAS.

REINFORCED COMPOSITE BUILDING BLOCK.

Application filed April 10, 1922. Serial No. 551,019.

To all whom it may concern:

Be it known that I, UNO E. TUOMI, a citizen of Finland, residing at Dallas, in the county of Dallas and State of Texas, have invented certain new and useful Improvements in Reenforced Composite Building Blocks, of which the following is a specification.

This invention relates to new and useful 10 improvements in reenforced composite building blocks.

The object of the invention is to provide a reenforced building block of the hollow type in which an air space is provided between the parallel slabs and the latter are secured in fixed relation by metallic bonding means.

A particular object of the invention is to provide metallic bonding means adapted to 20 be embedded in the slabs and which are also utilized in reenforcing the block longitudinally.

Another aim is to provide a block which is very simple in construction, but is substantial and durable and adapted to endure heavy strains, and which is less expensive to produce than other blocks of the hollow type now in use.

In carrying out the invention I provide 30 two substantially parallel plastic slabs which are spaced apart and secured in fixed relation by a pair of inter-locking or inter-engaging bonding elements embedded therein. Each of said elements is bent upon itself to 35 form a loop and a pair of intersecting bonding arms with elongated right angle extensions. The elements are disposed in inverted relation and the extensions of the one engage within the loop of the other, said extensions 40 reinforcing the block longitudinally while the said loops serve as keepers for the extensions and prevent spreading thereof.

A construction designed to carry out the invention will be hereinafter described together with other features of the invention.

The invention will be more readily understood from a reading of the following specification and by reference to the accompanying drawings, in which an example of the 50 invention is shown and wherein:

Fig. 1 is a perspective view of the bonding elements assembled,

Fig. 2 is a similar view of one of the elements separately,

Fig. 3 is a reduced side elevation of a 55 building block constructed in accordance with my invention,

Fig. 4 is a plan view of the same,

Fig. 5 is an enlarged cross section on the line 5—5 of Fig. 4,

Fig. 6 is a plan view of a corner block, and

Fig. 7 is a partial side elevation of the corner of a wall constructed of said blocks.

In the drawings the numeral 13 designates the face slab and 13' the inner slab of 65 a block embodying the invention. These slabs are substantially rectangular and parallel, and it is to be understood that the same may be molded of any suitable plastic material and to form any desirable design. The 70 said slabs are connected so as to provide an intermediate air space by means of a pair of metallic bonding elements which may be formed of wire or other like material.

Each bonding element is bent upon itself 75 to form a loop 10 and a pair of intersecting bonding arms 11, which are disposed at substantially 45 degree angles. The arms 11 of each element have a pair of elongated right angle extensions 12 which constitute reinforcing rods. The said elements are assembled or interlocked by arranging the same in inverted relation, whereby the ends of the extensions 12 of each are adapted to engage 80 within the loop 10 of the other.

The bonding elements are adapted to be embedded in the slabs by placing the same in interlocked position in the mold forming 85 said slabs and pouring the plastic material therein in the usual manner, as is obvious.

As will be best seen in Figs. 4 and 5, when the block has been formed a pair of bonding arms 11 are located slightly inwardly of each end. The corresponding angular portions of the loops 10 together with the ends 95 of the arms 11, are embedded in the slabs; the arms of each pair intersecting and being disposed at 45 degree angles. By the inverted relation of said elements a loop 10 is embedded in the upper portion at one end 100 of the block, while at the opposite end of the block the loop is located in the lower portion. It will be seen that by the angular arrangement of the arms 11, the same form substantial braces and secure the slabs in 105 fixed relation.

The elongated extensions 12 are embedded in the upper and lower portions of the said

slabs throughout their length, whereby the same are reenforced longitudinally. It is pointed out that the ends of the said extensions are passed through the loops 10 which have the function of keepers, thereby locking the bonding elements together and preventing the extensions or reinforcing rods from spreading.

It will be seen that a building block constructed in accordance with the invention is well reinforced and bonded and is substantial and durable. The block is highly desirable because of its simple and inexpensive construction. It is pointed out that the bonding elements may be formed of wire, and by virtue of their dual function, the use of separate reinforcing means is obviated.

In Fig. 6, I have illustrated a corner block with a closed or solid end, such blocks to be used at the end of a wall to form a corner, as is shown in Fig. 7. To construct a corner it will be seen that the end blocks of intersecting walls may be laid at right angles so that their outer portions overlap. As the blocks are twice as long as their width, it will be seen in Fig. 7, that by such construction the joints will be properly broken. It is to be understood, however, that Fig. 6, and 7, merely show one form of corner block that may be used and the invention is in no way limited to such a block with a closed or solid end.

Various changes in the size and shape of the different parts as well as modifications

may be made without departing from the spirit of the invention.

What I claim, is:

1. A building block, a pair of substantially parallel slabs spaced apart, and bonding elements embedded in and connecting said slabs, each of said elements being bent upon itself to form a loop and a pair of intersecting bonding arms terminating in elongated substantially right angle extensions, the extensions of each element being disposed longitudinally within the slabs and received by the loop of the other element. 45

2. A bonding connection adapted to be embedded in and connect separated slabs of a building block, said connection including 50 pairs of intersecting bonding arms terminating in elongated extensions adapted to be disposed within and reinforce the said slabs longitudinally.

3. A bonding connection adapted to be embedded in and connect separated slabs of a building block, said connection including two corresponding elements each bent upon itself to form a loop and a pair of intersecting bonding arms terminating in elongated 55 extensions, the extensions of each element adapted to be embedded in and reinforce the said slabs longitudinally and to engage in the loop of the other element, whereby the elements are interlocked and the said extensions are prevented from spreading. 65

In testimony whereof I affix my signature.
UNO E. TUOMI.
